UNITED STATES PATENT OFFICE.

CHARLES E. HOPKINS, OF PLAINFIELD, NEW JERSEY.

MACHINE FOR MAKING CURVED STEREOTYPE PRINTING-PLATES.

1,286,325.

Specification of Letters Patent.

Patented Dec. 3, 1918.

Application filed December 19, 1911; Serial No. 666,645. Renewed December 7, 1917. Serial No. 206,075.

To all whom it may concern:

Be it known that I, CHARLES E. HOPKINS, a citizen of the United States, formerly residing at Taunton, in the county of Bristol 5 and State of Massachusetts, but now residing at Plainfield, county of Union, and State of New Jersey, have invented a new and useful Machine for Making Curved Stereotype Printing-Plates, of which the following is a specification.

This invention relates to improvements in molds for casting curved stereotype printing plates, mechanism for delivering the plates from the molds, mechanism for trimming and shaving the plates, and for thereafter delivering the trimmed and shaved plates to the cooling mechanism, and improvements in said cooling mechanism.

The principal objects of the invention are 20 to reduce the detail elements to a minimum as near as possible at the present time, to reduce the space occupied by all the elements necessary for producing curved stereotype printing plates ready to be immediately attached to the cylinders of rotary web printing presses; to provide for utilizing the waste water from the cooling chamber of the casting mechanism to cool the finished stereotype plates, and to again 25 utilize it further as a means for operating mechanism for delivering cast stereotype plates from the casting chamber and to aline them with the finishing mechanism, and thereafter by automatically discharging 30 the said water to cause the casting chamber to close automatically and position the cooling mechanism so as to receive the finished stereotype plate from the finishing mechanism. Further objects of the invention 35 are to cool the core more rapidly than heretofore; to provide mechanism of such a character that a much simpler form of matrix holding and releasing means can be employed than heretofore; to dispense with 40 the flexible hose or pipes for conveying water to and from the cooling chamber formed in the core, and to utilize the weight 45 of the waste water from the cooler to operate the mechanism for delivering the cast 50 plate from the casting chamber; to provide automatic means for moving the pouring sheet free from the cast and lifting it out of the way so that the stereotype plate can be moved for finishing; also to dispense with 55 the sliding or pivoted bottom ring supports

which have been used in some previous inventions, to provide means whereby as the casting chamber is opening and the core turning on its pivot out of the way, the frame carrying the cast plate is caused to 60 roll and turn out of casting position to a horizontal position into axial alinement with the finishing mechanism; and to provide a construction in which during this rolling and turning movement the pouring 65 sheet engages stops which cause it to separate from the plate. In this way by separating the plate from the core before delivering the plate in horizontal position, I am able to cause lugs formed on the concave side of the riser portion of the stereotype plate to come into engagement with corresponding openings made in the extending arms of a conveying means.

The invention also dispenses with the 70 principle of casting the straight edges of the curved stereotype lower than the type face, which in practice made it necessary to make the cast considerably longer than the type face, and also made it necessary to 75 alter the type chases so as to form a wide flat groove at both the top and bottom of the type matrix; and it also dispenses with the necessity of changing the plate margin bars on the printing press cylinders so as 80 to allow of the extra length of plate entering between the aforesaid bars. I secure all the advantages of casting the straight 85 margin low by positioning the matrix clamp jaws so as to engage the flat margins outside of the ordinary bolster, and position the side bars of the plate carrying frame so as to overlap, but not engage, the raised bolster, in doing which a thin long lip is 90 formed on each straight side of the curved plate; and I utilize this lip as a guiding 95 means for the plate as it is moved into position in the finishing mechanism and by a simple mechanism separate this lip or guide from the plate as it is being pushed in the 100 cooling mechanism.

Among the objects of the part of the invention relating to the finishing mechanism are the following:—A riser or slug is separated from the type portion of the stereotype plate by an entirely new principle, dispensing with the revolving planetary saw mechanism and the separate means for carrying the riser free from the machine. In order to accomplish this I employ a 110

simple tool so mounted that it revolves at considerable speed about the axis of the knife shaft and simultaneously advances toward and through the stereotype plate 5 (locked in the arch) from the concave or axis side and at the proper angle to form the necessary bevel while separating the riser from the type portion of the plate. During this operation the shaving knife 10 shaft makes one complete revolution carrying the knife which trues up the ribs cast on the concave side and beneath the type face of the stereotype plate. In this invention I employ a hand operated conveyer for 15 moving the stereotype plate from the casting mechanism and positioning it in the finishing mechanism, and thereafter moving both the type face portion and the separated riser out of the finishing mechanism. 20 The type face portion is moved over the revolving straight edge finishing cutters and into position on the cooling mechanism, and the riser is moved on the projecting rails of the cooling mechanism. In this way the 25 finished plate as well as the riser are delivered back in the same position as when picked up by the conveyer, and the conveyer is thus brought to proper position to engage the finished plate. The parts are also left 30 directly in front of the operator so that he can pick up the riser and place it in a chute to convey it to the melting pot, then, in operation, he opens the valve controlling the flow of water to the cooler. Thereupon the 35 water rushes into a distributing pipe positioned in the spray pipe and thereafter into engagement with the concave surface of the finished stereotype plate thereby cooling the plate so that it can be handled. The 40 parts are designed so that while the shaving and trimming takes place the operator can reposition the matrix, close the casting chamber, and pump the chamber full of metal, it being remembered that the act of 45 closing the chamber moves the cooler into position to receive a plate and slug from the finishing mechanism.

The invention also involves a safety locking means through which it is impossible to 50 start the finishing mechanism if the conveyer or plate lifter is not in proper position or to raise a plate into position in the shaving arch unless it is in exact position to be finished. Means is also provided whereby 55 the operation of the finishing mechanism can be checked at any time, and means for automatically stopping the finishing mechanism after each cycle.

Further objects and advantages of the invention will appear hereinafter.

Reference is to be had to the accompanying drawings in which—

Figure 1 is a side view of a machine constructed in accordance with this invention 65 showing the parts in position for casting

and the cooling mechanism alined with the finishing mechanism, part of the side frame being broken away to show interior construction;

Fig. 2 is a side elevation of the same with 70 the casting chamber opened and showing the plate carrying frame supported over the inclined core and a stereotype plate (sectional) supported in the finishing mechanism, certain parts being in longitudinal 75 cross section;

Fig. 3 is a plan of the machine with the casting chamber open and the arch of the finishing mechanism removed, and part of the pouring sheet broken away; 80

Fig. 4 is a plan of the casting and cooling mechanism with the casting chamber closed;

Fig. 5 is a front end elevation with the parts in the same position with the straight edge finishing mechanism removed; 85

Fig. 6 is a fragmentary front end elevation showing the mechanism for closing and opening the matrix clamps;

Fig. 7 is a sectional view on the line 7—7 of Fig. 2 showing the casting chamber 90 opened and the stereotype plate resting on the side bars of the plate carrying frame;

Fig. 8 is a central longitudinal sectional view with the parts in the position shown in Fig. 2; 95

Fig. 9 is a fragmentary plan showing the mechanism for moving a matrix clamp in open position as in Fig. 3 with the parts above removed;

Fig. 10 is a horizontal sectional view on the line 10—10 of Fig. 1 on enlarged scale;

Fig. 11 is a central longitudinal sectional view of a portion of the finishing mechanism showing the tail severed from the plate; 105

Fig. 12 is a fragmentary side view partially diagrammatic showing two positions of the core;

Fig. 13 is a transverse sectional view on the line 13—13 of Fig. 2 showing the finishing mechanism in elevation; and 110

Fig. 14 is an end elevation of the machine.

The invention is shown in a form comprising a frame A, an upright concave fixed back B, plate carrying frame C, core D, 115 cooling device E, conveyer F, shaving arch G, and finishing device H. The concave back as stated is mounted vertically between the two side frames at one end with its concave side facing the opposite end of the 120 frame. At each straight side of the back supported by brackets 20 are vertical shafts 21 to which are fixed extending arms 22. These are shown most clearly in Fig. 10. Each of these arms is provided with hinges 125 23 for supporting a matrix bar 24 having a lip 25. When the bars are in closed position upon the straight sides of the back these two lips extend within the concavity of the back and overlap the straight margins of a 130

flexible matrix *m* when positioned within the back, as shown in full lines in Fig. 10. That portion of each hinge 23 which is attached to the bar 24 has an extension 26 normally held against the outside face of the extending arm 22 by a spring 27 when the matrix clamp is in open position. When the matrix clamps are being closed pins 28 fast on each bar 24 engage the straight sides of the back and force the bars 24 to turn on their hinges simultaneously with the movement of the arms 22. This causes the lips 25 to swing first within and then toward the concavity of the back and engage the flat matrix margin and push it solidly against the concavity of the back. That portion 29 of the concavity of the back lying under each lip 25 is formed on a radius from the axis of the pivot shaft 21 so that in opening the casting box the lips can swing forth from the back while the bars 24 are held in alignment with the arms 22, by the lips engaging a plate carrying frame C.

To avoid changing all the margin bars on the press, at considerable expense, and the reduction of the length of the type matter of each page, and at the same time form a guide on each cast plate, I position the sides of the plate carrying frame C so as to overlap but not engage the raised bolster of the matrix, (Fig. 10) and position the matrix clamp bars 24 so as to engage the usual flat margin of the edge of the matrix. In this arrangement I also dispense with alterations necessary in the iron chases which form a frame about each page of type matter, for molding the wide flat bolsters.

By combining the sides of the plate carrying frame C and matrix clamp bars, as above stated the stereotype plate P is formed with an extending lip P^2 along each outside straight edge; this lip is used as a guiding means during the action of conveying the plate from the casting mechanism to and from the finishing mechanism, and is removed by edge trimming cutters.

The two matrix clamps are made to operate in unison through links 31 and 32 fast on the bottom ends of the shafts 21. (Fig. 3). On the link 32 is mounted a roller 33 which operates in a slot 34 in the link 31. The pivot end of the link 31 is formed with teeth 35 which engage corresponding teeth in a rock foot treadle 36 pivoted on the side frame. This treadle is operated when it is desired to commence the casting operation for the purpose of closing the matrix clamps. The link 32 near its pivot has a projecting arm 37 which carries a spring actuated latch 38 to engage with a pin 39 carried on one of the core supporting brackets 40. The object of this latch is to open the matrix clamps and release the matrix automatically when the core begins to turn on its pivot from vertical position toward

open position. In Fig. 9 the pin 39 is in position to ratchet over the latch as the core is closed into the back.

The bottom of the mold is closed by a half-ring 41, the inner or upper edge of which is formed with a bevel for forming the required bevel on the lower curved edge of the cast plate P. This ring 41 of course joins the lower ends of the side bars 48 with which it is integral, preferably. On the upper ends of the side bars is mounted a cross shaft 42 upon which are mounted rollers 43 which co-act with the core as will appear hereinafter. The plate carrying frame C is mounted on rollers 45 which operate on tracks 46 formed on the top surface of the side frames A. These rollers 45 have studs which are mounted in bearings in brackets 47 formed on the side bars 48 of the frame. To the lower side ends of the side bars 48 are secured studs 49 carrying anti-friction rollers 50 which operate in vertical ways 51 on the side frames A.

The core D is pivoted to the frame A by the brackets 40 fast to its bottom end. These brackets are mounted in bearings 53 on cross pieces 54. An inlet water pipe 55 and an outlet water pipe 56 are arranged at opposite ends of said hollow bearings on the brackets 40. The inlet pipe 55 enters the water chamber 57 of the core at the bottom, (Fig. 8). The outlet pipe extends along the concave side of the core and into the chamber 57 near the top. Both the inlet and outlet pipes are provided with swivel joints 58 in line with the core pivot axes (see Fig. 5). This permits the pipes to move with the movement of the core. A controlling valve 59 is positioned in the inlet pipe so that the operator can regulate the supply of water.

Each straight side of the core D is provided with matrix clamp lug-stops 60 which, when the casting chamber is closed, move into engagement with the straps of the hinges 23 to force the bars 24 of the matrix clamps solidly against the straight edge of the back, (see Fig. 10). To the top straight sides of the core are attached brackets 61 each having a flat surface for engaging the rollers 43 on the plate carrying frame C in opening the casting chamber. This causes the frame C to move away from the back and through the guiding means to be described herein-after to turn the frame into horizontal position.

Mounted vertically on the top of the bearings 53 in which the core turns are reciprocal matrix positioning stops 65 (Fig. 1). These are forced up by springs 66 into position to receive the bottom curved edge of the matrix when being positioned. After the matrix *m* is positioned and clamped by the closing of the matrix clamps, the stops 65 are forced down by the tail ring 41 of the plate carrying frame. This occurs as the

- frame moves into casting position within the concavity of the back.
- The convex face of the core D is provided with the usual grooves 660 forming ribs on the interior face of the plate P under the type matter and is also provided with a recess 67 on each side near the top for forming conveying lugs P' which co-act with the conveyer F as will be described hereinafter.
10. A pouring sheet 68 is provided which is arranged to engage and overlap the upper end of the matrix when the casting chamber is closed. It is attached to side plates 69 which are held in position by studs 70 fixed to the sides of the plate carrying frame C. The studs 70 extend through slotted holes 71 in the side plates 69 which allow the side plates, with the pouring sheet attached, to be raised as the plates engage stops 72 on 20 the side frames A, while the plate frame is turning to horizontal position (Fig. 3).
- Each straight side of the core is provided with a fixed side frame 80. Extending through these side frames and operating in bearings 81 is a shaft 82 having an operating handle 83 on the front side. To each end of the shaft is fixed an arm 84. Sliding in dove-tailed ways 85 on the outside face of each of the frames 80 and located near the 30 core are plungers 86. These are operatively connected by links 87 to the arms 84. Mounted on each of a pair of studs 88 (Fig. 4) which connect the arms 84 and links 87 is an antifriction roller 89. To the side frames A are made fast brackets 90 having cam faces against which the rollers 89 operate in locking the core into casting position. These parts are so arranged that in order to lock the core in casting position the operator 40 pushes down on the handle 83 whereupon the rollers 89 engage the cam face of the brackets 90 and as the movement continues the core is forced into and locked in casting position. When the core is in casting position the swinging of the handle 83 in the opposite direction causes the plungers 86 to bear on the under sides of the plate carrying frame C. Upon continuing the movement the core is thus forced away from the frame 50 and the cast stereotype plate left therein.
- Positioned between the frames 80 is the plate cooling mechanism E which comprises a waste water pan 96 having an outlet drip valve 97 positioned at its bottom when the core is in its open position. This opening is so located that it is directly over the flaring end of a waste pipe 98 fixed into the floor upon which the machine stands. The said waste pipe has a projecting rod 99 which engages and opens the drip valve 97 during the final movement of the core and delivery of the stereotype plate. This discharges all the water from the pan, the purpose of which will be described hereinafter.
60. Cross pieces 101 and 102 are provided to

box in the concave ends of the stereotype plate when resting on the guide way on the top side of the side frame 80. These prevent the water from flying out. Cross piece 102 is of such size that the plate will pass 70 over it and the cross piece 101 is slightly larger than the concavity of the plate so as to act as a positioning stop therefor. Extending through the cross piece 101 at the axis of its curve is a water feed pipe 103 75 which is connected with the waste water pipe 56 of the core. Positioned in the feed pipe 103 is a push valve 104. That portion of the feed pipe 103 that extends between the cross pieces is enveloped by a spray pipe 80 105. The feed pipe 103 has perforations through which water can flow downward into the spray pipe 105. These parts are axially aligned between the cross pieces 101 and 102 and directly over the waste water 85 pan 96. The spray pipe 105 has numerous perforations through its upper half which flare outwardly so that when the water is forced through the perforations it will form one mass of fine sprays instead of the small 90 streams that would be produced by straight openings. A rod 108 extends across the waste water pan 96 and supports one end of a cover 109 extending about half way over the opening. This cover 109 prevents 95 the water from overflowing as the cooler is tipped in opening the casting chamber.

A counter-balance 110 for the core and cooler is pivoted on the rear frame beneath the finishing mechanism H and is connected 100 by a flexible connection 111 which passes over a grooved pulley 112 with a short arm 113 extending down and forming part of the rear side frame of the cooler. This flexible connection, preferably in the form 105 of a wire rope, is guided over a rod 114 extending out from the side frame to prevent the rope from interfering with the core locking mechanism. For the purpose of holding the core D in open position against 110 the weight of the counter-balance 110 after the waste water has been discharged, a locking hook 115 is pivoted in the front frame by a short shaft 116 which extends out through a bearing in the frame. Fast to 115 this short shaft is a foot treadle 117 extending at about right angles from the hook. The treadle is provided with a counter-weight 119. When the hook is in engagement with a pin 120 positioned on the front 120 frame of the cooler, the core is firmly held in open position. When the parts are brought to open position the pin 120 passes over the inclined edge of the hook and the counter-weight brings the hook back to locking position.

Having described the casting and cooling mechanism shown in the drawings, I will now describe the specific mechanism illustrated for shaving off the ribs cast on the 130

50 interior surface of the type portion of the plate, separating the riser from and trimming the straight edges of the type portion of the plate and conveying the plate to and from 5 that portion of the machine.

The side frames are provided with ledges 130 on which is supported the arch G slightly out of axial alignment with the stereotype plate when it rests on the plate carrying 10 frame in horizontal position. The interior circumference of the arch is slightly less than the exterior of the type face portion of the curved stereotype plate. The driving shaft 131 of the machine operates in bearings 132 formed upon the cross frame 133. On the driving shaft is a bevel gear 134 which meshes with and drives a bevel gear 135 fast on a short shaft 136. This short shaft operates in a bearing 137 formed in 15 the cross frame 133. Fast on this shaft 136 is a gear 138 meshing with a gear 139 loosely mounted on the knife shaft 140. The shaft 131 is provided with a worm 141 fast thereon which drives a worm gear 142 on the 20 knife shaft 140. In this way the knife shaft is driven slowly. The knife shaft is axially aligned with the arch and supported in bearings 143 at either end. A shaving knife 144 is fixed to a flange 145 formed along that 25 portion of the knife shaft underneath the arch.

Loosely mounted upon the knife shaft 140 is a support 148. It is attached to and made to travel around with the gear 139, which 30 is loosely mounted on the knife shaft as has been stated. On this support is a tool holder 149 set at an angle. Extending beyond the arch and knife and underneath where the riser portion of the stereotype plate rests 35 when in position to be shaved and trimmed is a simple trimming tool 150 in the tool holder. Said tool and holder are carried by the support 148 loosely mounted on the knife shaft 140. Fastened to the knife shaft bearing 143 on the frame 133 and axially positioned with respect to the knife shaft is a 40 round box or cover 151. This envelops the gear 139 and is provided with a cam groove 152 formed in its internal face. Loosely 45 keyed on the knife shaft 140 so as to rotate with it is a sleeve 153. One end of the sleeve is shaped to form a disk 154 and to the opposite end is fastened an arm 155 carrying a roller 156 which operates in the cam 50 groove 152. The disk 154 is made to operate in a groove 157 formed in and near the inner end of the tool holder 149. Upon each revolution of the knife shaft the cam 152 causes the disk to advance slowly, thereby causing 55 the tool to pass through the stereotype plate, separate the riser, and thereafter quickly return.

It will be seen that while the knife is caused to make one revolution with its shaft 60 140, the trimming tool 150 is caused to re-

volve at considerable speed about the axis of the knife shaft 140, and to advance simultaneously at the proper angle away from this axis until it is engaged by the stereotype plate held in the arch. It cuts its way 70 through so as to separate the riser from the type face and properly bevel off the curved edge of the plate. (See Fig. 11.)

For the purpose of stopping the knife shaft 140 and co-acting mechanism after 75 each cycle of operations, the following mechanism is shown:—A clutch mechanism is provided between the driving pulley 160 and the driving shaft 131 on which this pulley is loosely mounted. This clutch mechanism comprises a movable jaw 161 on the driving shaft, and an opposite jaw 162 fixed to a sleeve 159 loose on the shaft 131. The movable jaw is caused to travel with the shaft through a sliding key 163. The sleeve 80 159 extends through the shaft bearing and the driving pulley 160 which is keyed to it so that when the clutch jaws are disengaged the pulley 160 and its co-acting jaw 162 can continue to run while the knife shaft and 85 co-acting parts are at rest.

The clutch is held out of operation by the following mechanism:—A roller 164 is fast on a cross bar 165 and engages in a groove 166 of the slide jaw 161. A pin 167 positioned 90 on the face of the knife shaft worm gear 142 engages a projection 168 on the cross bar 165. The cross bar is forced toward the engaged position by a spring 169. The clutch end of the cross bar is positioned 100 against the rear cross shaft bearing 132. It operates about a stud 181 fast on said bearing. The front end, however, is made to operate in a slot formed on the front bearing 132. Therefore, the cross bar can be 105 lowered sufficiently to release its projection 168 from engagement with the pin 167 on the worm gear. This cross bar 165 is removably held in raised position by a connecting link 184. Said link is connected by 110 a stud 185 to an arm 186 fast on a trip treadle shaft 187. On this shaft is a trip 188 which is pressed down to pull down the connecting link and disengage the crossbar projection 168 from engagement with the stop pin 167 on the worm gear, thereby 115 starting that part of the mechanism.

On the main driving shaft 131 is the main driving pulley 160 which by a belt drives a flanged pulley 123 on the end of a shaft 125 supported in a bracket 126 fixed to the frame A. When the cooler is aligned in position to receive a plate, a friction pulley 127 on the shaft 125 engages another friction pulley 128 mounted on a shaft 129. The shaft 129 is positioned near the ends of the cooler frame in bearings, (see Figs. 2 and 4) and upon it are mounted circular straight edge cutters K which are let into the guide way. 125 130

I will now describe the mechanism F illustrated in the drawings for conveying, lifting and locking the stereotype plate in position in the arch, and thereafter conveying it back to the edge trimmers and water cooling mechanism. The stereotype plate lifter and guide ways consist of two long bars 170 and 171 arranged with their edges nearly alined with, but below, the straight edges 5 of the arch G and tied together by cross bars 172 at each end. The plate lifting frame is pivoted to brackets 173 (Figs. 3 and 14) which are fast on ledges formed at the top of the rear side frame A. The front 10 side of the lifter frame is supported by a stud operating in one end of an arm 174, the opposite end being joined by a stud 175 to one end of a second arm 176, extending upward from a rock shaft 177. This consequently forms a toggle mechanism through 15 which the operator can raise the lifter and stereotype plate into position in the arch by moving a lever 178 fast on one end of the said shaft 177.

Extending across the machine is a rock 20 shaft 180 operated by a hand lever 281. On this rock shaft and alined with the plate lifter are fixed telescoping arms 282, the top of these arms being joined by a stud 283 to slide pieces 284. These slide pieces 25 are moved back and forth in recesses 285 formed on the inside faces of the bars 170 and 171 by the aforesaid connections. To the slide pieces 284 are fastened extending 30 arms 286 each having a recess 287 into which 35 engages the lug P' of the stereotype plate to be conveyed. Positioning stops 288 are placed in the path of the arms 286 for the purpose of stopping the forward movement 40 of the conveying mechanism so as to properly position the stereotype plate beneath and within the arch ready to be lifted and thereafter shaved and trimmed.

For the purpose of preventing the 45 machine being put out of commission through any forgetfulness on the part of the operator, mechanism is provided in the form of safety stops, safety lugs, and trip to make it impossible to start the finishing mechanism unless the different operations have 50 been carried out in the proper order and to make it impossible to move any part of the machine by hand during the cycle of movement after it has been started. The conveyer must move forward and come into 55 contact with stops 288 on the frame and the plate lifter must be elevated before the operator can trip and thereby start the mechanism. The act of tripping the starting 60 mechanism locks the plate lifter in its elevated position, and at the same time locks the conveyer and it becomes impossible to move either the lifter or conveyer so long as the mechanism is in motion. If it is nec-

essary, however, for any cause to stop the 65 mechanism before it finishes its cycle of operation, the operator simply steps on a trip treadle and the mechanism comes to rest. This mechanism will now be described. On the toggle arm 176 is positioned a bar 190 70 to engage a bearing 191 formed on the face of the front telescope arm 282 at all times except when the conveyer is in engagement with the positioning stop 288, in which position, the bearing 191 is beyond the forward 75 end of the bar 190 and the plate lifter can be elevated by the straightening out of the toggles which straightening moves the forward end of the bar 190 beyond the bearing 191 on the face of the telescope arm and 80 thereby locks the conveyer between the bearing 191 and the positioning stop 288. To prevent the movement of the bar 190 from behind the bearing 191 on the telescoping arm during the operation of the machine, 85 there is arranged on the end of the toggle shaft 177 a short arm 192. When the toggles are extended the short arm 192 engages the end of a rocking lock arm 193 on a short 90 shaft 194. On this shaft 194 also is an arm 195 connected to the cross bar 165. The operation of the bar 165 causes the lock arm 193 to move into the path of the short arm 192 on the toggle shaft and locks the toggles in the extended position. At the same 95 time a hook 196 positioned on the toggle shaft 177 will be disengaged from under a projection 197 formed on the arm 186 on the trip shaft 187 on which is located the trip treadle 188 for releasing the trip so that the operator can start the mechanism. As the mechanism nears the end of the cycle of motion the pin 167 on the gear 142 engages the projection 168 on the cross bar 165 and forces the bar to withdraw the 100 clutch jaws from engagement whereupon the mechanism stops. In case it should become necessary to stop the mechanism before the end of the cycle the operator pushes down heavily on the trip treadle 188. This 105 movement causes the arm 186 to act with the treadle movement and bring a projection 198 into engagement with the connecting link 184 between the arm 186 and the cross bar 165. This causes the bar 165 to be 110 forced forward so as to throw the movable member of the clutch out of engagement. The treadle 188 is provided with a counterbalance weight 200 to hold the pedal and 115 connecting parts in operative position.

The operation is as follows:—Starting with the casting chamber open and the core D withdrawn in the position shown in Fig. 2, the operator curves the flexible matrix to suit the concavity of the back and lowers it 120 into engagement with the bottom matrix stops 65. He then places his foot on the rock treadle 36 and pushes toward the rear.

This causes the matrix clamps to swing inwardly on their pivots and carry the bars 24 over the straight position in the concave back. Having thus positioned the matrix 5 he now releases the locking hook 115 which holds the core in open position whereupon the core counter-balance 110 causes the said core to rise and swing inwardly on its pivots toward the back. This allows the plate 10 carrying frame C to turn on its pivots into vertical position within the back and the further movement of the core toward the back brings the plungers 86 on the side of the cooler into position. Then the operator 15 pushes down on the operating handle 83 and thereby locks the core and frame in position for casting.

The operator now fills the casting chamber, in any usual manner, as by means of a 20 pump or ladle. After allowing the proper time for cooling the operator presses down on the handle 83 which acts to first unlock the locking device and thereafter separates the core D from the plate carrying frame C 25 in which the cast plate is now held. If there is no cast in the finishing mechanism H to be cooled during the solidifying of the metal in the casting chamber, the operator should open the water valve 59 to allow sufficient water to run into the cooler basin to 30 act as a counter-weight to deliver the cast plate.

The cast plate now being delivered with the plate carrying frame resting on the 35 frame A the operator grasps the hand lever 281 and pushes toward the finishing mechanism. This moves the stereotype plate off the plate carrying frame C and positions it in the finishing mechanism H. Having the 40 plate located he pushes in on the lever 178 to operate the toggles 174-176 and raise the stereotype plate up into the locked position in the arch G. The plate is now in position for finishing. To start the finishing mechanism the operator pushes down lightly on the trip treadle 188.

While the finishing mechanism is operating he repositions the matrix for another cast 45 or positions a new matrix, closes the casting chamber, and fills the chamber with metal. It is during this time that the finishing mechanism operates to separate the riser from the type face of the stereotype plate as well as to true off the ribs beneath the type 50 face. The finishing mechanism having finished its cycle of operation stops automatically as has been stated. The operator by first pulling out on the lever 178 lowers the toggle mechanism and allows the stereotype 55 plate to come down from engagement with the arch. Then he reverses the lever 281 and pushes the riser and type face portion out of the finishing mechanism over the straight edge tools and into position on the 60 straight edge tools and into position on the 65

cooler. He picks up the riser and returns it 65 to the melting pot through the ordinary chute, (not shown) or by hand, and then opens the water supply by pushing down on the push valve 104. As soon as the plate 70 sufficiently cools, he lifts it free from the machine by hand and then proceeds with the series of operations again.

Although I have illustrated and described a preferred embodiment of the invention showing details of the various mechanisms, 75 I am aware that the principles of the invention can be carried out in other forms and with other details of construction. Therefore I do not wish to be limited to the details herein shown and described, but what I do 80 claim is:—

1. In a stereotype plate casting apparatus, the combination with a fixed back, of a core 85 movable toward and from the back, and means independent of the core at all times between the core and back for moving the cast plate from the back.

2. In a stereotype plate casting apparatus, the combination with a mold half, of a second mold half movable toward and from the 90 first mold half, and means independent of the second mold half for moving the cast plate from the casting apparatus in a path different from, but adjacent to, the path of the second mold half. 95

3. In a stereotype plate casting apparatus, the combination with a fixed vertical back, of a core adapted to move into the back, and means movable independently of the core but in the plane of the core and back for moving a cast plate from the back and lifting its lower end to bring the plate into substantially horizontal position. 100

4. In a stereotype plate casting apparatus, the combination with a fixed vertical back, 105 of a core pivoted to said back near the lower end thereof, whereby said core can be swung on its pivot into the back and away from it, and a plate carrying frame arranged to move from a vertical position adjacent to the back 110 into a substantially horizontal position over the core with a plate thereon.

5. In a stereotype plate casting apparatus, the combination with a back, of a core, and means independent of both back and core 115 for moving the cast plate from between said core and back into a position directly over the core when withdrawn from the back.

6. In a stereotype plate casting apparatus, the combination with a back, of a core, one 120 fixed and the other movable away from it, means for holding a cast plate in the fixed part as the movable one is moved away from it, and means for delivering the cast plate directly from the fixed part in the same direction in which the movable part moves. 125

7. In a stereotype plate casting apparatus, the combination with a back, of a core adapt-

ed to swing out of the back, and a plate carrying frame movable independently of the core from the casting box into inclined position and movable from inclined position to horizontal position over the core.

8. In a stereotype plate casting apparatus, the combination with a back, of a core pivoted thereto near the bottom thereof and adapted to swing out of the back on its pivot, and a plate carrying frame movable independently of the core by a pivotal motion from the casting box into inclined position and movable from inclined position to horizontal position over the core.

15. 9. In a stereotype plate casting apparatus, the combination with a frame having a vertical casting box fixed thereon, of a core pivoted near the bottom thereof to swing from the casting box, and a plate carrying frame independent of the core having a pivot about which it is adapted to swing from the casting box into inclined position, said frame having means for guiding said pivot longitudinally to bring the plate carrying frame into substantially horizontal position.

30. 10. In a stereotype plate casting apparatus, the combination of a frame having a vertical back fixed thereon and provided with vertical slots near the edge of said back, of a plate carrying frame having studs extending into and guided by said slots, whereby said plate carrying frame can swing into the back and can move outwardly from the back and its lower end can then be raised in the slots.

35. 11. In a stereotype plate casting apparatus, the combination of a frame having a vertical back fixed thereon and provided with vertical slots near the edges of said back, of a plate carrying frame having studs extending into and guided by said slots, and a horizontal guide on said frame for the support of said plate carrying frame.

45. 12. In a stereotype plate casting apparatus, the combination with a concave back, of a guide parallel with the straight edges thereof, a plate carrying frame having a stud movable along said guide and a transverse guide for the other end of the frame.

50. 13. In a stereotype plate casting apparatus, the combination with a back and a core, of a plate carrying frame movable from vertical to horizontal position and comprising a bottom ring, two side members, and a pouring sheet, with means whereby the pouring sheet is raised to separate from the cast plate as the carrying frame turns to horizontal position.

60. 14. In a stereotype plate casting apparatus, the combination with a back and a core, of a plate carrying frame, having a pouring sheet attached to opposite straight edges of the frame, and means for separating the pouring sheet from the cast plate without disconnecting either end of said sheet from the frame.

15. In a stereotype plate casting apparatus, the combination with a vertical back, of a core pivoted to said back near the lower end thereof, a plate carrying frame arranged to move from the back into a substantially horizontal position with a plate thereon, matrix clamps carried by the back, and means movable with the core for locking said clamps in closed position.

16. In a stereotype plate casting apparatus, the combination with a back having matrix clamps adapted to swing inwardly toward its edges, of a core movable toward and from the back, and matrix clamp locks mounted on said core for forcing the clamps radially inward against the outside straight edges of the back.

17. In a stereotype plate casting apparatus, the combination with an upright back having vertical matrix clamps at its edges, of a core movable toward and from the back, a shaft on the core having arms thereon, links connected with said arms, and plungers on said links, for releasing the core.

18. In a stereotype plate casting apparatus, the combination with a back, of a core pivoted to it, a pair of matrix clamps located at the edges of the back, a shaft for each matrix clamp, means for connecting said shafts to operate simultaneously, a lever for operating said shafts, a treadle for operating the lever, and means co-acting with the core whereby said matrix clamps can be operated simultaneously to open as the core turns on its pivot.

19. In a stereotype plate casting apparatus, the combination with a back, of a pair of shafts thereon, matrix clamps on said shafts, each having an arm thereon, one arm having a slot, and the other a pin working in said slot, whereby the oscillation of one shaft will cause the other to be oscillated.

20. In a stereotype plate casting apparatus, the combination with a back for supporting a matrix, of a shaft carried by said back, a two-part arm on the shaft having a pivot between its parts, and means on the outer part of the arm for clamping the matrix against the back.

21. In a stereotype plate casting apparatus, the combination with a back for supporting a matrix, of a shaft carried by said back, an arm on the shaft having a pivot between its ends, means on the end of the arm for clamping the matrix against the back, and positive means for swinging the outer end of the arm inwardly toward the casting box faster than the rest of the arm.

22. In a stereotype plate casting apparatus, the combination with a casting box, of a matrix clamping arm mounted to swing on a pivot and provided with a pivot joint between its ends, the outer end having a projection extending inwardly beyond the joint,

and positive means for engaging said extension as the arm moves toward the box to cause the outer end of the arm to swing inwardly at a more rapid rate than the rest 5 of the arm.

23. In a stereotype plate casting apparatus, the combination with a casting box, of a matrix clamping arm pivoted thereon having a pivot joint between its ends, the outer 10 end being provided with two projections extending inwardly beyond the pivot joint, a spring for engaging one of said projections to hold the outer end yieldingly away from the box, and positive means for moving 15 the outer end of the arm toward the box as the arm swings inwardly.

24. In a stereotype plate casting apparatus, the combination with a casting box, of a matrix clamping arm pivoted thereon in 20 two parts hinged together, and means for moving the outer part of the arm toward the box on its hinge as the whole arm swings inwardly, said arm having a transverse projection on its outer end arranged to overlap 25 the edges of a matrix held in the box and to extend substantially to the bolster thereof.

25. In a stereotype plate casting apparatus, the combination with a vertical back, 30 of a core arranged to swing outwardly from the back into inclined position, matrix clamps on the back, and manually controlled means mounted on the core for engaging the back when the core is in position therein 35 and effecting a separation between the core and back.

26. In a stereotype plate casting apparatus, the combination with a vertical back, of a core arranged to swing outwardly from 40 the back into inclined position, matrix clamps on the back, manually controlled means mounted on the core for engaging the back when the core is in position therein and effecting a separation between the core and 45 back, and a counter-balance weight for the core to normally turn it to vertical position within the back.

27. In a stereotype plate casting apparatus, the combination with a back, of a core, 50 means mounted on the core for engaging the back when the core is in position therein and effecting a separation between the core and back, and a counter-balance weight for the core to normally turn it to position within 55 the back.

28. In a stereotype plate casting apparatus, the combination with a vertical back, of a core arranged to swing outwardly from the back into inclined position, matrix 60 clamps on the back, manually controlled means mounted on the core for engaging the back when the core is in position therein and effecting a separation between the core and back, and a gravity catch for automatically locking the core in its inclined position 65

away from the back, whereby when the gravity catch is tripped the counter-weight will tend to swing the core up into the back.

29. In a stereotype plate casting apparatus, the combination with an upright back, 70 of a core pivoted thereto near the bottom, a counter-balance for the core, a locking device for locking the core in retracted position, and a treadle for releasing the core from the locking device. 75

30. In a stereotype plate casting apparatus, the combination with the core pivoted to swing about a pivot, a pivoted counter-weight for the core, a pulley above the counter-weight, and a flexible connection passing 80 over the pulley, one end being connected with the counter-weight, and the other with the core.

31. The combination with a stationary casting box or back, of a movable core, a 85 resiliently mounted matrix positioning stop at the end of the back for receiving the edge of the matrix when being positioned, and a tail ring movable into the back for engaging the stop and forcing it down. 90

32. In a stereotype plate casting device, the combination with a casting box, of a plate carrying frame for delivering a plate from the casting box having side bars overlapping the raised bolster of the matrix to 95 form a thin, long lip on each straight side of the curved plate.

33. In a stereotype plate casting apparatus, the combination of a cooling device for cooling a cast plate, means for delivering 100 cast plates from the casting box, means whereby the cooling water operates to assist said means for delivering the cast plates, and means for automatically discharging the water to cause the casting chamber to close 105 automatically.

34. In a stereotype plate casting apparatus, the combination with the back, a movable core, a counter-weight for the core, means for cooling the cast plate, and means 110 for holding the cooling medium in position to over-balance the counter-weight.

35. In a stereotype plate casting apparatus, the combination with a pivoted core having means for introducing a cooling medium therein, and a trough for receiving the cooling medium therefrom located in position for the cooling medium received therein to act as a weight to assist in moving the core on its pivot. 115 120

36. In a stereotype plate casting apparatus, the combination of a core pivoted beyond one end thereof, means for introducing a cooling fluid into the core through the pivot, a pipe carried by said core and connecting with the pivot for receiving the cooling fluid therefrom, a device for cooling the plates connected with said pipe for receiving cooling fluid therefrom, and a trough for receiving the cooling fluid from said 125 130

- cooling means and having means for automatically discharging the cooling fluid when the core swings over to the extreme position on its pivot.
- 5 37. In a stereotype plate casting apparatus, the combination with a back, of a core pivoted thereto, means for introducing a cooling fluid into the core axially through the pivot, and means connected with the interior of the core and projecting transversely from the side thereof for conducting the cooling fluid from the core and applying it to the cast plate.
- 10 38. In a stereotype plate casting apparatus, the combination with a back, and a core movable toward and from the back, of a cooling device for the plates projecting transversely from the side of the core opposite the back.
- 15 39. In a casting box, the combination of a hollow cylindrical core, a spray pipe having outwardly flaring perforations through the side thereof adjacent to the curved walls of the core, and a feed pipe extending into said spray pipe and connected with a source of water supply and provided with perforations therein on the side opposite the perforations in the spray pipe.
- 20 40. In a stereotype plate casting apparatus, the combination with a casting box and finishing means spaced therefrom, of a movable core having cooling means in position to cool a plate while supported independently of the core and located between the casting box and finishing means.
- 25 41. In a stereotype plate casting apparatus, the combination with a casting box and finishing means spaced therefrom, of a movable core having cooling means in position to cool a plate located between the casting box and finishing means, while the core is in casting position in the back.
- 30 42. In a stereotype plate casting apparatus, the combination with a casting box and finishing means spaced therefrom, of a movable core having cooling means in position to cool a plate located between the casting box and finishing means, and means for withdrawing a cast plate from the back independently of the core and placing it in position over the core between the casting box and finishing means.
- 35 43. In a stereotype plate casting apparatus, the combination with a casting box and a core movable toward and from the same, of a finishing means, means for moving a cast plate into position in alinement with the finishing means, and trimming saws mounted on the core in position to trim the edges of the plate as it moves from the finishing means.
- 40 44. In a stereotype plate casting apparatus, the combination with a vertical back, of a core arranged to swing outwardly from the back into inclined position, matrix clamps on
- the back, manually controlled means mounted on the core for engaging the back when the core is in position therein and effecting a separation between the core and back, a finishing mechanism, a driving shaft for 70 the finishing mechanism, a friction pulley operated by said driving shaft, and edge trimming cutters movable with the core and having a friction pulley thereon adapted to come into contact with the first named friction pulley when the core is moved into position in the back.
- 75 45. In a stereotype plate casting apparatus, the combination with a back and a movable core, of a support for a plate in position adjacent to the core when the core is in casting position in the back, edge trimming cutters carried by said core, a friction pulley fixed with respect to the edge trimming cutters, a finishing mechanism located 80 beyond the said plate support, and a friction pulley operated by the finishing mechanism and located in position to be engaged by the first named friction pulley and to drive it when the core is in casting position.
- 85 46. In a stereotype plate casting apparatus, the combination with a back and a movable core, of a finishing mechanism, edge trimming cutters carried by the core, and means connected with the finishing mechanism for driving the edge trimming cutters when the core is in casting position.
- 90 47. In a stereotype plate casting apparatus, the combination with a back and movable core, of a finishing mechanism, a support 100 for a plate located between the back and finishing mechanism, edge trimming cutters movable with the core and in position to trim the edge of a plate moving to said support from the finishing mechanism, 105 and means connected with the finishing mechanism for operating said cutters when the core is in casting position in the back.
- 105 48. In a stereotype plate casting apparatus, the combination with a back and core, of a shaving device, an edge trimming device, and means for conveying the plates into the shaving device, and then conveying them back toward the back to the edge trimming device.
- 110 49. In a stereotype plate casting apparatus, the combination with a back and movable core, of a finishing device, a support for the cast plate between the back and finishing device, and a conveyer movable 115 into position to deliver the cast plate after it is delivered from the casting box on said support and also movable from said position through the finishing device and back to original position, and having means for 120 operatively engaging the cast plate during all of said motion.
- 125 50. In a device of the character described, the combination of a support for a cast stereotype plate, a finishing device, and a 130

- reciprocating conveyer having a notch for receiving a portion of the cast plate and movable from a position between the support and finishing device to the opposite end of the finishing device and back again, and arranged and adapted to retain its hold on the cast plate during its entire operation.
51. In a device of the character described, the combination of a support for a cast stereotype plate, a finishing device, means for raising a cast plate in the finishing device to seat it therein, and a conveyer having a notch for receiving a portion of the cast plate and movable from a position between the support and finishing device to the opposite end of the finishing device and back again, and arranged and adapted to retain a hold on the cast plate during the entire motion.
52. In a machine of the class described, the combination of a casting device, a finishing device, a support for the cast plate located between the casting device and finishing device, means for transferring the plate from the casting device to the said support, and means for moving the plate from said support into the finishing device and for thereafter moving the plate back on the support.
53. In a machine of the class described, the combination of a casting device, a finishing device, a support for the cast plate located between the casting device and finishing device, means for transferring the plate from the casting device to the said support, and means for moving the plate from said support into the finishing device and for thereafter moving the plate back on the support, the last named means comprising a reciprocating conveyer for engaging the plate while on the support and retaining its engagement with the plate while in the finishing device.
54. In a stereotype plate apparatus, the combination of a vertical casting mechanism with a horizontal finishing mechanism alined therewith, a conveyer in alinement with the casting and finishing mechanism, said casting mechanism having means for forming means on the cast plate for engaging the conveyer, and means for delivering the plate from the vertical casting position to a horizontal position and in engagement with the conveyer.
55. In a machine for finishing curved stereotype plates, the combination of a plate support, an arch, means for conveying a plate from the support, to and beneath the arch, means for holding the plate in the arch, means for shaving the interior of the plate, means for separating the riser from said plate, edge trimming tools, a cooling mechanism and means for moving the plate from the arch by the tools and to the cooling mechanism.

56. In a stereotype plate casting apparatus, the combination of a casting box, a finishing mechanism, cooling device for cooling a cast plate, means for delivering cast plates from the casting box, means whereby the cooling water operates to assist said means for delivering the cast plates, and means for automatically discharging the water to cause the casting chamber to close automatically, and to position the cooling mechanism to receive the finished plate from the finishing mechanism.

57. In a stereotype plate machine, the combination with a casting device, of an arch for receiving the plate, a support between said arch and casting device for receiving the plate from the casting device, and means for engaging the plate while on the support, moving it into the arch, and moving it back again on the support.

58. In a stereotype plate machine, the combination with a casting device, of an arch for receiving a plate, a support substantially in axial alinement with the arch for receiving a plate from the casting device, means for raising a plate in the arch, and means for engaging a plate on said support, moving it into the arch, retaining its engagement therewith, and moving it back again on the support.

59. A transferring device for stereotype plates, comprising means adapted to swing about an axis arranged transversely with reference to the plate, said swinging means having devices adapted to engage the plate and hold it while it is lifted out of the casting apparatus and transferred to a suitable support.

60. A transferring device for curved stereotype plates, comprising a frame having side bars adapted to engage and support the straight edges of a plate and provided with an end ring adapted to engage and support the end of the plate, and means on said frame, whereby when the frame is drawn back one end will move horizontally and its other end will move up until the frame is in horizontal position.

61. A transferring device for curved stereotype plates, comprising a frame having side bars adapted to engage and support the straight edges of a plate and provided with an end ring adapted to engage and support the end of the plate, a horizontal track, a vertical guide, and means whereby when the frame is drawn back its upper end will move horizontally along the track and its lower end will move up along the guide until the frame is in horizontal position.

62. A transferring device for curved stereotype plates, comprising a frame having side bars adapted to engage and support the straight edges of a plate and provided with an end ring adapted to engage and support the end of the plate when the plate is sub-

stantially in vertical position, a horizontal track, a vertical guide, and means on said frame for engaging the track and guide, whereby when the frame is drawn back its 5 upper end will move horizontally along the track and its lower end will move up along the guide until the frame is in horizontal position.

63. A transferring device for stereotype 10 printing plates comprising means independent of the casting back for engaging a plate, said engaging means being movable to lift the plate from one part of the casting apparatus and transfer it to a suitable 15 support.

64. A transferring device for stereotype 20 printing plates comprising means independent of the casting back for engaging the plate, said engaging means being movable to lift the plate and swing it about an axis to a suitable support located at a level 25 above the center of the casting back.

65. In a stereotype plate casting apparatus, the combination of a casting box, 30 a cooling device for cooling a cast plate, means for delivering cast plates from the casting box, means whereby the cooling water operates to assist said means for delivering the cast plates, and means for automatically discharging the water to cause the casting chamber to close automatically.

66. In a stereotype plate casting apparatus, the combination of a casting box, a finishing mechanism, a cooling device for 35 cooling a cast plate, means for delivering cast plates from the casting box, means whereby the cooling water operates to assist

said means for delivering the cast plates, and means for automatically discharging the water to position the cooling mechanism 40 to receive the finished plate from the finishing mechanism.

67. In a machine for casting curved stereotype printing plates, the combination with a vertical casting box, of means for taking the cast plate therefrom independently of the back and core of said casting box and swinging it through an angle. 45

68. In a machine for making stereotype 50 printing plates, the combination with a mold for the plate, of a frame mounted adjacent thereto, means on said frame for engaging the plate, and separating it from both the back and core of said mold when the frame moves away from the mold, and 55 guideways in position for receiving the plate from said separating means.

69. The combination with a vertical mold 60 part for a concave printing plate, of a swinging frame pivoted at the end of said mold part to swing on a transverse axis carrying a second mold part, means independent of the swinging frame for engaging the plate on said mold part and taking it away therefrom and from the swinging 65 frame, and guideways for receiving the plate from said frame longitudinally.

In testimony whereof I have hereunto set my hand, in the presence of two subscribing witnesses.

CHARLES E. HOPKINS.
